UNITED STATES PATENT OFFICE.

WILLIAM PAUL BUTUSOV, OF NORFOLK, VIRGINIA.

POWER PLANT.

1,423,514.

Specification of Letters Patent. Patented July 25, 1922.

Application filed January 24, 1921. Serial No. 439,467.

To all whom it may concern:

Be it known that I, WILLIAM P. BUTUSOV, a citizen of the United States, residing at Norfolk, in the county of Norfolk and State 5 of Virginia, have invented certain new and useful Improvements in Power Plants, of which the following is a specification, reference being had to the accompanying drawings.

10 This invention relates to power plants, and it is an object of the invention to provide a device of this general character embodying novel and improved means wherein in a wind driven element is operatively engaged with an electrical generator and 15 wherein the electricity generated thereby is conveyed to an accumulator or storage battery.

Another object of the invention is to provide 20 a novel and improved mechanism of this general character particularly designed and adapted for use in connection with a boat and wherein such mechanism is provided with means for generating and storing 25 a supply of electrical energy and which energy may be employed as desired.

The invention consists in the details of construction and in the combination and arrangement of the several parts of my 30 proved power plant whereby certain important advantages are attained and the device rendered simpler, less expensive and otherwise more convenient and advantageous for use, as will be hereinafter more 35 fully set forth.

The novel features of my invention will hereinafter be definitely claimed.

In order that my invention may be the better understood, I will now proceed to describe 40 the same with reference to the accompanying drawings, wherein:

Figure 1 is a view partly in side elevation and partly in section illustrating a boat having a mechanism constructed in accordance with an embodiment of my invention applied thereto.

Figure 2 is an enlarged fragmentary view partly in elevation and partly in section of the propeller shaft and parts 45 comitant thereto as herein embodied, and

Figure 3 is a horizontal sectional view taken through the wind-driven rotatable element.

As disclosed in the accompanying drawings, H denotes the hull of a boat in which 50 is suitably mounted an electrical genera-

tor G of any ordinary or preferred type. The generator G is in electrical connection with the storage batteries S of any desired type.

Extending upwardly from the deck of the boat at longitudinally spaced points thereon are the masts 1 which rotatably support at a desired point above the deck of the boat a horizontally disposed shaft 2. The opposite end portions of the shaft 2 have fixed thereon the propellers P of a conventional construction.

Loosely mounted on the shaft 2 between the propellers P is an elongated sleeve 3. 70 Fixed to one end portion of the sleeve 3 is a pulley 4 around which passes a belt 5, said belt 5 being in driving connection with the generator G.

The pulley 4 is provided with an outer 75 clutch face 6 with which coacts a clutch member 7 keyed to the shaft 2 but having movement lengthwise thereof so that said clutch member 7 may be engaged or disengaged at will with the pulley 4. The sleeve 3 is 80 held against endwise movement lengthwise of the shaft 2 by the collars 8 locked to the shaft 2 and coacting with the opposite ends of the sleeve 3.

Surrounding the sleeve 3 and keyed thereto for rotation therewith but capable of movement lengthwise thereof is an elongated hub or sleeve 9 provided at its opposite end portions with the reversely related beveled pinions 10 adapted to separately mesh with 90 a beveled gear 11. The gear 11 is fixed to the upper end portion of a vertically disposed shaft 12 rotatably supported at its lower end portion, at 14, by the boat and at its upper end portion by a bearing 15 carried 95 by the frame F. The frame F is suitably mounted upon the boat.

Suitably fixed to the shaft 12 is a wind-driven rotatable element W comprising a central cylindrical body 16 having extending outwardly from the periphery thereof the vertically disposed vanes 17, each of said vanes 17 being arranged horizontally on a desired incline with respect to the radius of the body 16. The outer vertical edges of 100 the vanes 17 are tied or connected by the annular members 18 positioned adjacent the tops and bottoms of said vanes 17 and whereby the vanes are effectively maintained in a fixed position.

Operatively engaged with one end portion 110 of the sleeve 9 is a lever 19 adapted to be

operated in any desired manner but herein disclosed as being capable of movement upon a point adjacent the stern of the boat through the instrumentality of properly associated rods and levers. The lever 19 is supported for swinging movement by the upper portion of the frame F.

Upon requisite swinging movement of the lever 19, the sleeve 9 may be adjusted to cause either of the pinions 10 to mesh with the gear 11 or said pinions 10 may both be brought into a neutral position or free of the gear 11. It will be obvious that when one of the pinions 10 is in mesh with the gear 11, the shaft 3 will be rotated in a direction reverse to the direction of rotation when the second pinion 10 is in mesh with the gear 11.

The frame F is provided with an extension 20 which supports a swinging lever 21 operatively engaged with the clutch member 7 so that said member 7 may be moved into or out of locking engagement with the clutch face 6 of the pulley 4 when required. As disclosed in Figure 1 of the accompanying drawings, the lever 21 may be readily operated from a point at the stern of the boat by a plurality of associated rods and levers.

As the element W rotates under force of the wind, the generator G will be driven and the electrical energy created thereby will be conveyed to and stored in the batteries S and this generating of the electrical energy is preferably accomplished when the boat is moored or at anchor. When the element W is rotating to generate electrical energy, the clutch member 7 is preferably in release position.

The electrical energy stored in the batteries S may be used for any purpose desired but it will be obvious that, if desired, this current may be employed to operate the generator G as a motor whereupon the sleeve 3 will be rotated, together with the shaft 1, when the clutch member 7 is in locked engagement with the clutch face 6 of the pulley 4. By this means, the stored energy may be used as a source of power for propelling the boat through the instrumentality of the propellers P.

From the foregoing description it is thought to be obvious that a power plant

constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. The combination with a movable body including a deck, an upstanding frame carried by the deck, the deck and frame having vertically opposed bearings, a wind driven element rotatably supported by said bearings, a shaft supported by the deck above the frame, a sleeve mounted upon the shaft for driven connection with the wind driven element, coacting means carried by the shaft and the sleeve for causing the shaft and sleeve to rotate in unison, said means including a member keyed to the shaft for rotation therewith and for movement lengthwise thereof, and means carried by the frame for imparting movement to the member lengthwise of the shaft.

2. The combination with a movable body including a deck, an upstanding frame carried by the deck, the deck and frame having vertically opposed bearings, a wind driven element rotatably supported by said bearings, a shaft supported by the deck above the frame, a sleeve mounted upon the shaft for driven connection with the wind driven element, coacting means carried by the shaft and the sleeve for causing the shaft and sleeve to rotate in unison, said means including a member keyed to the shaft for rotation therewith and for movement lengthwise thereof, means carried by the frame for imparting movement to the member lengthwise of the shaft, and means operating independently of the last named means for imparting movement to the sleeve lengthwise of the shaft to disconnect the sleeve and the wind driven element.

In testimony whereof I hereunto affix my signature.

WILLIAM PAUL BUTUSOV.
